UNITED STATES PATENT OFFICE.

EDGAR KIDWELL, OF MILWAUKEE, WISCONSIN, ASSIGNOR TO KIDWELL BOILER COMPANY, OF MILWAUKEE, WISCONSIN, A CORPORATION OF WISCONSIN.

STEAM BOILER.

Application filed September 5, 1923. Serial No. 661,017.

This invention relates to water-tube boilers of the series tube and drum type, and more particularly to means for supporting the main transverse baffle wall above the lower bank of water tubes of such boilers.

The object of the invention is to provide a baffle wall supporting structure which is effectually protected from the destructive action of the hot furnace gases, and which 10 structure constitutes a part of the circulating system of the boiler, as will be herein-after described and claimed.

The invention is herein illustrated in connection with a water-tube boiler of the character described in Letters Patent of the 15 United States No. 1,442,433 dated January 16, 1923, but it is to be understood that the improvements are equally applicable to water-tube boilers of other forms or types.

20 In the drawings—

Figure 1 is a longitudinal vertical section of a battery type of boiler embodying my invention.

Fig. 2 is a transverse section of the boiler, 25 as on the line 2—2 of Fig. 1.

Referring to the drawings, 10 designates the boiler setting, which, in the present illustration, is medially divided by a central partition wall 10' to afford two chambers or 30 compartments for the respective boiler units. 11 designates one of the combustion chambers, and 12 designates the outlet or breeching to the smoke stack at the rear of the setting. 13 designates a mud drum at the rear 35 of the bridge wall of each combustion chamber; 14 a water drum located above the forward portion of the said chamber and below the normal water level, and 15, 16 two steam-and-water drums arranged above the drums 40 13, 14, respectively. The drums 15, 13 and 14 are connected in succeeding order by banks of tubes 20, 21, 22 respectively, thereby providing a continuous circulation path for the boiler water. The steam spaces of 45 the two upper drums are connected by overcomer tubes 24 whereby the steam which is disengaged from the water in the drum 15 flows into the steam space of the front upper drum, whence it is removed for service. The 50 water spaces of the upper drums are connected by means of opposite-flow tubes 26, 27 which function to establish a supplementary water circulation between the two drums and maintain therein a uniform water level, as

more fully described in Patent No. 1,442,433 55 aforesaid.

Suitable baffling is arranged within the boiler setting to provide succeeding passes for the hot gases in their course from the combustion chamber at the front to the outlet at the rear of the setting, which baffling

includes a main transverse wall 28 of fire-brick or other refractory material, supported directly above the lower tube bank 21

that overhangs the combustion chamber, and 55 also a wall 28' located within the bank of tubes 20 to extend from the drum 15 to a plane somewhat above the mud drum 13. As

illustrated these baffle walls provide two up and one down serial passes for the gases be- 60

tween the combustion chamber and the outlet or off-take. The wall 28 is sustained by 65 a basal girder 29 supported in the boiler setting, which girder, in large boilers, has

an extensive span and must, for safety, be 70 protected from the destructive action of the hot furnace gases. Accordingly, provision

is made for the efficient water cooling of the 75 girder as follows: The girder comprises a hollow trunk-like structure which is sup- 80

ported at its ends in the walls of the boiler setting, the outer end, in the present instance, being conveniently closed by means

of a cap 30. The girder is communicably 85 connected adjacent each end thereof to the top of the mud drum 13 by means of a tube 31, and it is also similarly connected, about midway between its ends, to the bottom of

the rear steam-and-water drum 15 by means 90 of one or more tubes 32, such girder and tubes being exposed to the hot gases in their travel.

By this construction a water circuit is established between the drums 13, 15 and 95 the girder, and, in consequence, there is maintained throughout the interior of the girder a continuous circulation of boiler water which effectually protects the girder walls from the destructive action of the hot furnace gases; and since the girder and its

tube connections constitute an integral part 100 of the circulating system they serve ef- ficiently to augment the heating surface of

the boiler. It is to be noted that the placing 105 of the tubes 31, 32 in the path of the gases, and especially the arrangement in the upper

and hotter portion of the down pass, of the tubes 32 which connect the support with the

steam-and-water drum 15, materially assist

in causing a rapid circulation of water through the support, thus ensuring an efficient cooling effect of the water on the support.

It is to be understood that my invention is not limited to the structural details herein disclosed, as the construction may be modified within the principle of the invention and the scope of the appended claims.

I claim—

1. A water tube boiler comprising a setting having a combustion chamber therein and an off-take for the products of combustion, a mud drum, a steam and water drum, water circulating tubes connecting the mud drum to the steam and water drum, a baffle forming serial passes for the gases between the combustion chamber and the off-take, a hollow water cooled support for said baffle, water circulating connections between the mud drum and the hollow support in the path of the gases, and water circulating connections between the hollow support and the steam and water drum also in the path of the gases and in a hotter portion of the pass than the connections between the hollow support and the mud drum.
2. A water tube boiler comprising a setting having a combustion chamber therein and an off-take for the products of combustion, a mud drum, a steam and water drum, water circulating tubes connecting the mud drum to the steam and water drum, a plurality of baffles forming two up, and one down serial passes for the gases between the combustion chamber and the off-take, a hollow water cooled support for the baffle between the first and second pass, water circulating connections between the mud drum and the hollow support in the lower portion of the down pass and in the path of the

gases, and water circulating connections between the hollow support and the steam and water drum in the upper portion of the down pass and also in the path of the gases. 45

3. A water tube boiler comprising a setting having a combustion chamber therein and an off-take for the products of combustion, a plurality of baffles therein which form serial passes for the gases from the combustion chamber to the off-take, a mud drum, a steam and water drum, a water drum between said drums, water circulating connections between the mud drum and the water drum, a hollow water cooled girder supported at its ends supporting a portion at least of one of the baffles, circulating connections between the mud drum and the hollow girder, and circulating connections between the girder and the steam and water drum in a down pass for the gases. 55 60

4. In a water-tube boiler comprising a setting, a combustion chamber, an upper steam-and-water drum, a lower mud drum, an intermediate water drum, banks of tubes connecting the drums in successive order, and baffling, including a transverse wall of refractory material, a hollow water cooled girder upon which said wall is supported above the tube bank leading from the mud drum to the water drum, tubes connecting the respective ends of the girder to the mud drum, and an intermediate tube connecting the girder to the said steam-and-water drum, said girder and its connecting tubes being arranged in the path of the gases from the combustion chamber. 70 75

Signed at Milwaukee, in the county of Milwaukee and State of Wisconsin this 24th day of August, A. D. 1923.

EDGAR KIDWELL.
